UNITED STATES PATENT OFFICE

157,098

COMBINED MUSIC STAND AND AMPLIFIER HOUSING

Harry Stanley, Rocky River, Charles Tancre,
Avon Lake, and Lawrence C. Roy, Strongsville,
Ohio

Application December 20, 1948, Serial No. 150,291

Term of patent 14 years

(Cl. D56—4)

To all whom it may concern:

Be it known that we, Charles Tancre, Harry Stanley, and Lawrence C. Roy, citizens of the United States and residents of Avon Lake, Ohio; Rocky River, Ohio; and Strongsville, Ohio, respectively, have invented a new, original, and ornamental Design for a Combination Music Stand and Amplifier Housing, shown in the accompanying drawing.

In the drawing:

We claim:

The ornamental design for a combination music stand and amplifier housing, substantially as shown.

HARRY STANLEY.
CHAS. TANCRE.
LAWRENCE C. ROY.
